UNITED STATES PATENT OFFICE.

WILLIAM C. WEAVER, OF ELIZABETHVILLE, PENNSYLVANIA.

RAIL-JOINT.

No. 835,587.

Specification of Letters Patent.

Patented Nov. 13, 1906.

Application filed March 23, 1906. Serial No. 307,687.

To all whom it may concern:

Be it known that I, WILLIAM C. WEAVER, a citizen of the United States, residing at Elizabethtown, in the county of Dauphin and State 5 of Pennsylvania, have invented certain new and useful Improvements in Rail-Joints, of which the following is a specification.

This invention embodies novel improvements in rail-joints; and the essential features of the invention are comprised mainly in the special means provided to secure an extended bearing at the point of jointure of the rails, obviating the usual rounding of the ends of these parts and the noise and vibration incident to the passage of the wheels of the rolling-stock thereover and special means being provided for attaching the rail ends together and obviating the necessity of use of bolts and nuts and giving rise to other advantages of importance.

For a full understanding of the invention and the merits thereof and also to acquire a knowledge of the details of construction of the means for effecting the result reference 25 is to be had to the following description and accompanying drawings, in which—

Figure 1 is a perspective view of a rail-joint embodying the invention. Fig. 2 is a longitudinal sectional view. Fig. 3 is a transverse 30 section taken through one of the transverse members securing the rails to the rail-chair. Fig. 4 is a transverse section taken through the double catch provided to engage the cam-lever.

Corresponding and like parts are referred to in the following description and indicated in all the views of the drawings by the same reference characters.

In carrying out the invention it is designed that the rails 1 shall be of substantially the same form as is most commonly in use at the present time—namely, T shape—the webs and bases of the rail ends being cut square and abutting against each other in the usual manner, while the heads are scarfed at the ends or cut away on a diagonal line, as shown at 2, in order that they will overlap and form a continuous bearing for the wheels of the rolling-stock to prevent the noise and vibration incident to the rounding-off of the rail ends in the usual formation thereof. The ends of the rails 1 are seated in the rail-chair 3, which comprises a base 4 and spaced wings or sides 5 to rest snugly against the opposite sides of the web of the rail. If desired, the sides 5 of the chair 3 may be reinforced

by suitable webs 6, connecting said sides with the base portion of the rail. The adjacent ends of the rails 1 are provided with transverse openings therethrough, which are adapted to register with openings in the sides of wings 5 of the rail-chair 3.

Transverse fastening members 7 pass through the registering openings of the rails and chair 3, and these fastening members 7 each consist of a body formed with a head 8 at one end and a vertical transversely-elongated opening 9 at the opposite end. The head 8 of each member 7 is adapted to bear against the outer face of one of the sides or wings 5, and the opening 9 of such member receives a vertical pin 10, carried by a cam-lever 11, which is adapted to be positioned upon the fastening member 7 in such a way that on pivotal movement of said cam-lever 75 the cam 12 will be brought to bear against the adjacent side of the chair 3 to secure the member 7 from displacement and necessarily to attach the rail, with which said member 7 co-operates, to the chair. The cam-lever 11, 80 which co-operates with each member 7, is detachably applied thereto, the pin 10 of such lever being formed with an elongated head 10^a at its lower extremity, adapted to pass through the elongated opening 9 and to engage with the under side of the member 7 after the lever 11 has been operated so as to force its cam 12 into positive engagement with the adjacent side of the chair 3. Such movement of the cam-lever 11 causes the 85 head 10^a of the pin 10 to assume a position transversely of the elongated slot or opening 9, thereby locking the lever 11 to the member 7 in such a way as to obviate likelihood of displacement of such lever. After the levers 90 11, which coact with the fastening members 7, have been so operated as to cause the cams 12 thereof to engage the opposite sides of the chair 3 (it being understood that the levers 11 will be arranged upon opposite 95 sides of the rails 1) said levers are held in such co-operative position by means of a double catch 13. The double-catch 13 consists of a transverse bar having the catch-noses 14 at opposite ends and formed with a laterally-projecting lug 15 intermediate of its ends. The member 13 is adapted to be passed through registering openings 16 in opposite 100 sides or wings 5 of the chair 3 and fits in notches in the web portions of the rail ends, 105 it being remembered that the said web portions are cut square, as has heretofore been

mentioned. The double catch member 13 is introduced into operative position by being passed flatwise through the openings 16 and then turned upwardly to cause the lug 15 to assume a vertical position between the wings 5 of the chair 3, so as to prevent lateral play, movement, or displacement of the catch. Such arrangement of the member 13 likewise so disposes the noses 14 that said 10 noses project upwardly in such a way that they may be readily engaged with the outer ends of the levers 11, as shown most clearly in Figs. 1 and 2 of the drawings.

The invention is comparatively simple in 15 its construction and is particularly advantageous by reason of the fact that it admits of quick application and detachment of the parts.

Having thus described the invention, what 20 is claimed as new is—

1. In a rail-joint, and in combination with the meeting ends of rails, a rail-chair, transverse fastening members passing through the rail ends and the sides of the chair, and cams 25 connected with said fastening members and operable to engage the chair to prevent displacement of such members.

2. In a rail-joint, and in combination with the meeting ends of rails, a rail-chair, trans- 30 verse fastening members passing through the rail ends and sides of the chair, said fastening members embodying a head at one end adapted to bear against a side of the chair, and cams at the opposite end of said fastening 35 members and operable to engage the opposite sides of the chair in the manner specified.

3. In a rail-joint, and in combination with the meeting ends of rails, a rail-chair, fastening members for securing the rails to the 40 chair and passing transversely through said rails and the side portions of said chair, a head at one end of each fastening member adapted to bear against one side of the chair, and a cam-lever applied to the opposite end 45 of such fastening member and arranged to bear against the opposite side of the chair to prevent displacement of the fastening member.

4. In a rail-joint, and in combination with the meeting ends of rails, a rail-chair, fastening members for securing the rails to the 50 chair and passing transversely through said rails and the side portions of said chair, a head at one end of each fastening member adapted to bear against one side of the chair, and cam-levers detachably connected with 55 the opposite end of each fastening member and having the cams thereof arranged to bear against the opposite sides of the chair for the 60 purpose specified.

5. In a rail-joint, and in combination with the meeting ends of rails, a rail-chair, fastening members for securing the rails to the 65 chair and passing transversely through said

rails and the side portions of said chair, a 65 head at one end of each fastening member adapted to bear against one side of the chair, the opposite end of each fastening member being provided with a pivot-pin opening, a cam-lever for each fastening member, a pivot- 70 pin projecting from the cam-lever and passing through the pivot-pin opening of the fastening member, and means for interlocking said pivot-pin with the fastening member, admitting of detachment of the cam-lever. 75

6. In a rail-joint, and in combination with the meeting ends of rails, a rail-chair, fastening members for securing the rails to the chair and passing transversely through said rails and the side portions of said chair, a 80 head at one end of each fastening member adapted to bear against one side of the chair, the opposite end of each fastening member being provided with a pivot-pin opening, a cam-lever for each fastening member, a pivot- 85 pin projecting from the cam-lever and passing through the pivot-pin opening of the fastening member, the pivot-pin of each cam-lever having an elongated head to pass through the pivot-opening of its fastening 90 member and adapted to interlock the cam-lever therewith, and catch means coöperating with the cam-levers to hold the same in operative position.

7. In a rail-joint, the combination of meet- 95 ing ends of rails, a rail-chair receiving said ends, transverse fastening members passing through the rail ends and the sides of the chair, cam-levers applied to said fastening members for the purpose specified, and catch 100 means coacting with said levers.

8. In a rail-joint, the combination of meet- 105 ing ends of rails, a rail-chair receiving said ends, transverse fastening members passing through the rail ends and the sides of the 110 chair, cam-levers applied to said fastening members for the purpose specified, and a double catch attached to the rail-chair and having catch-noses to coact with the cam-levers.

9. In a rail-joint, the combination of meet- 115 ing ends of rails, a rail-chair receiving said ends, transverse fastening members passing through the rail ends and the sides of the chair, cam-levers applied to said fastening members for the purpose specified, and a double catch passing through opposite sides 120 of the chair and provided with means for preventing displacement thereof from the chair, said catch having catch-noses to engage the cam-levers for the purpose specified.

In testimony whereof I affix my signature in presence of two witnesses.
